US00D618204S

(12) **United States Design Patent**
Andre et al.

(10) **Patent No.:** US D618,204 S
(45) **Date of Patent:** ** Jun. 22, 2010

(54) **ELECTRONIC DEVICE**

(75) Inventors: **Bartley K. Andre**, Menlo Park, CA (US); **Daniel J. Coster**, San Francisco, CA (US); **Daniele De Iuliis**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Portola Valley, CA (US); **Matthew Dean Rohrbach**, San Francisco, CA (US); **Peter Russell-Clarke**, San Francisco, CA (US); **Douglas B. Satzger**, Menlo Park, CA (US); **Calvin Q. Seid**, Palo Alto, CA (US); **Vincent Keane Seid**, legal representative, Los Gatos, CA (US); **Christopher J. Stringer**, Woodside, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/281,648**

(22) Filed: **Jun. 27, 2007**

(51) LOC (9) Cl. **14-03**

(52) U.S. Cl. **D14/203.7; D14/496; D14/203.3**

(58) Field of Classification Search .... **D14/496, D14/401, 435, 474, 483, 217, 137, 138, 160, D14/168, 356, 203.1–203.8, 507, 341–345, D14/374, 424; 345/156, 169, 173–179, 905; 715/727–729, 864; 710/1, 5, 8; 713/1, 600; 455/1.1, 1.7, 73, 344–347, 93, 95, 3.01–3.06, 455/550.1, 573.1, 566, 575.1, 575.3, 575.8; 370/342–344; 369/1, 2, 6–12; 463/43–47; 273/148 B**

(57) **CLAIM**

The ornamental design of an electronic device, substantially as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of an electronic device in accordance with the present invention;

FIG. 2 is a front view thereof;

FIG. 3 is a side perspective view thereof;

FIG. 4 is a rear view thereof;

FIG. 5 is a right side view thereof;

FIG. 6 is left side view thereof;

FIG. 7 is a top plan view thereof; and,

FIG. 8 is a bottom plan view thereof.

**1 Claim, 5 Drawing Sheets
